(57) **CLAIM**

The ornamental design for an eye testing apparatus as shown and described.

DESCRIPTION

1. Eye testing apparatus

1.1 is a top and front perspective view of an eye testing apparatus showing our new design;

1.2 is a top and rear perspective view thereof;

1.3 is a bottom and front perspective view thereof;

1.4 is a front elevation view thereof;

1.5 is a rear elevation view thereof;

1.6 is a left-side elevation view thereof;

1.7 is a right-side elevation view thereof;

1.8 is a top plan view thereof; and,

1.9 is a bottom plan view thereof.

(Continued)

The broken lines shown in the drawings depict portions of the eye testing apparatus that form no part of the claimed design.
